T. HUTNIKOW

DOLL'S VOICE

Original Filed Sept. 13. 1922

FIG. 1

FIG. 3

FIG. 2

FIG. 4

FIG. 5

FIG. 7

UNITED STATES PATENT OFFICE.

THEODORE HUTNIKOW, OF BROOKLYN, NEW YORK, ASSIGNOR TO VOICES INCORPORATED, OF NEWARK, NEW JERSEY, A CORPORATION OF DELAWARE.

DOLL'S VOICE.

Application filed September 13, 1922, Serial No. 587,888. Renewed November 19, 1927.

This invention relates to sound producing mechanisms and has to do more particularly with a device for simulating the cry of an infant.

5 One of the objects of the invention is to provide a simple, effective and compact mechanism of the type described, which may be easily incorporated into the body of a so-called "talking" doll, and which shall be 10 operative to produce the desired cry upon movements of the body of the doll.

Another object of the invention is to produce a sound producing mechanism of the type described which will be so constructed 15 that it is possible to cause the mechanism to emit distinct syllables, thereby simulating the "ma-ma" cry.

Another object of the invention is to provide a device of the type described, which 20 may be incorporated into the body of a doll, the device being so constructed that upon movements of the body of the doll, the device will be operated to give off a cry, or a series of cries, and being operated further 25 to produce such cries upon different changes in the position of the body of the doll.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will 35 be indicated in the appended claims.

In the accompanying drawing, wherein I have shown preferred forms of embodiment of my invention:

Fig. 1 illustrates a top plan view of the 40 device.

Figure 2 is a view in longitudinal cross-section, showing one form of the device.

Figure 3 is a top plan view of the construction illustrated in Fig. 4.

45 Figure 4 is a view partially in longitudinal cross-section of a device similar to that shown in Fig. 2.

Figure 5 is a view partially in longitudinal cross-section of a device having a plurality of sound producing means therein.

50 Figure 6 is a view in transverse cross-section on the lines 6—6 in Figure 5; and

Figure 7 is a detail view in perspective of the valve mechanism.

55 Referring now to the drawing, wherein

similar reference characters refer to similar parts throughout the several views thereof, the reference character 1 designates a tubular container providing the exterior casing for the sound producing device. This casing will preferably be constructed of heavy 60 cardboard, fibre, or other like material, and will be preferably cylindrical in form.

Disposed at one end of the casing, and closing this end, is the head 2, made of 65 material similar to the body of the casing. There will also be provided intermediate the ends of the casing a second head 3. Mounted at one end in the casing 2 is a central guide post 4, made of light wire or other 70 similar material. This post passes through an aperture formed in the head 3, and extending nearly to the open end of the casing.

Mounted on the inner face of the head 3, and in the closed chamber formed between 75 the two heads, is a bellows 5, which will be in the form of a circumferentially creased cylinder made of rubberized fabric, or other suitable air tight material. One end of the bellows 5 will be fastened, as indicated at 80 6, to the inner face of the head 3, while there is mounted in the other end of the bellows a weighted disc 7, this disc serving to close the bellows, and to provide an operating mechanism for the device, as will later 85 be described.

Mounted in the aperture in the disc 7, through which the rod 4 extends, and closely encircling this rod, is an actuating member 8, this member being in the form of a cylindrical sleeve, one end of which is anchored in the disc 7, the other end extending through the head 3. This sleeve is movable with the disc through the head 3. Disposed near the end of the sleeve, or actuating member 8, 90 beyond the head 3, are spaced fingers 9 and 10, these fingers being designed to extend some little distance beyond the surface of the sleeve.

Mounted on the outer face of the head 3, is an orifice chamber 11, which will be constructed of light metal, this chamber being provided with an orifice 12 in its upper face. The chamber 11 has projecting into it, as will be seen in the dotted lines in Figure 1, a reed which in turn provides communication between the chamber 11 and a reed chamber 14, which is in turn in communication with the interior of the bellows. 100

It will thus be seen that upon a collapse 105

110

of the bellows, air will be forced through the reed chamber 14, through the reed 13, into the orifice chamber 11. The reed is so designed that upon expansion of air from the interior of the bellows the reed will be caused to vibrate and give off a high pitched cry.

Mounted on the upper surface of the orifice chamber 11, on a suitable pivot 15, is a spring-held valve, this valve having a flap 16, which is provided with a soft face 17 formed of leather, or other material of that character, the flap being so adjusted that it will normally press the face 17 so as to cover the orifice 12.

15. Encircling the pivot is a spring 18 which normally holds the valve open so that the orifice is unrestricted. At the rear end of the valve there is provided a bent arm 19, this arm being provided with the U-shaped portion 20, across the legs of which is disposed a thin flexible membrane 21, this membrane being so positioned that the edge will be engaged by the fingers 9 and 10.

20. The operation of the device is as follows: The voice mechanism will be placed in the body of the doll in such a position that when the doll is moved, for instance to the reclining position, a cry will be emitted. To attain this result the voice is disposed so that upon such movement of the doll, the weighted disc 7 will be caused to move under the influence of gravity to collapse the bellows. This movement will cause the air to be expelled from the bellows, thereby producing a vibration of the reed and the incidental cry.

25. As the disc moves, however, it will move the sleeve 8 with it, and the finger 9 will strike against the edge of the membrane 21, forcing the valve 16 to close the orifice 12. This closure will shut off the air movement, and consequently cause the reed to be still. The disc, however, continues a steady movement, and in a short interval of time the finger 9 will slip off the edge of the membrane 21, which will stretch enough to permit such movement.

30. The valve being then free, will be caused to return to the open position of the spring 18, whereupon a reed will again commence to vibrate. This is followed in a short instance of time by the second closing of the orifice by the finger 10. As the finger 10 in turn slips beyond the edge of the membrane 21, the orifice will be opened and the reed again caused to vibrate.

35. It will thus be seen that there will be produced a plurality of syllables caused by the action of the fingers and the valve. This action is such as to produce a series of syllables, such as "Ma-ma-ma". Obviously, the number of fingers on the actuating sleeve may be increased or decreased, as desired, and it will also be possible to vary the spacing therebetween, thus causing the produc-

tion of various other syllables as may be desired.

40. When the bellows is completely collapsed, the sound of course ceases, and when the doll is restored to position so that the action of gravity will cause the disc to move to the position illustrated in Figure 2, air will be drawn into the bellows through the orifice 12, through the chamber 11, thence through the reed and the reed chamber 14. On this return movement of the air, however, no sound will be produced, inasmuch as the reed is so disposed that the increase of the air will force the vibrating member from its seat. When the bellows is restored to the extended position, the series of operations may be repeated by removing the doll so as to release the weight and cause a second collapse of the bellows.

45. In the device as modified in Figure 4, the parts are somewhat reversed. In this position the bellows 5 is anchored to the head 2, and the weighted disc 7 takes the place of the head 3. The sleeve 8' with the actuating fingers 9 and 10 thereon, is now fast in position on the rod 4. The orifice chamber, the reed chamber, and the valve are in all respects similar to that previously shown in Figure 2, but these members are now mounted on the disc 7. The action of the device is in all respects similar to that previously illustrated, except that the sleeve 8, as has been explained, is now fast in position, and the disc 7 with the orifice chamber and the valve, move past the fingers as the bellows is collapsed.

50. The fingers 9 and 10 will again cause the valve to be closed, thus cutting off the action of the reed and there will again be produced a "ma-ma" cry, as has previously been explained.

55. In the type of device illustrated in Figures 5 and 6, the construction is similar to that shown in Figure 2, except the lower end of the casing is provided with a second chamber 22, having a perforated head 23 therein.

60. Disposed on the head 2 is a reed chamber 24 in communication through an orifice 25 with the chamber formed between the heads 2 and 3. The action of the device is similar to that illustrated in Figure 2 upon collapse of the bellows, but when the bellows is expanded this will displace air from the chamber between the heads 2 and 3 and this air forced through the orifice 25 will cause the reed 26 to vibrate, this action, however, being continuous. In the type of the device shown in Figure 5, there will be produced a "ma-ma-ma" cry when the bellows is collapsed, but upon the expansion of the bellows the reed 26 will be caused to give off a single continuous note.

65. It will be seen that I have provided a device well adapted to attain the aims and ob-

jects previously set forth. The sound producing mechanism proper is under complete control, and may be provided with actuating members so that any combination of syllables desired may be sounded. Obviously in use for a doll it will be desirable to have a reed with a high pitch note to simulate a cry of an infant, and it will be seen that the device is well adapted for rough usage, 10 such as will be given a toy of the type for which this device is intended.

The device is well protected, most of the working parts being enclosed, and those of which are not so concealed being protected 15 by the casing 1, which extends for some distance beyond the path of travel of the working parts. The device is cheaply constructed, and not likely to be easily injured, or otherwise put out of order.

20 As many changes could be made in this construction without departing from the scope of the following claims, it is intended that all matter contained in the above description or shown in the accompanying 25 drawing shall be interpreted as illustrative only and not in a limiting sense.

Having thus described my invention what I claim as new and desire to secure by Letters Patent is:

30 1. A device of the class described, comprising in combination, sound producing means, and means to control the sound produced, said last named means including an orifice chamber, a valve pivotally mounted 35 to close said orifice, the said valve having an arm provided with a U-shaped portion, a resilient actuating membrane disposed on said U-shaped portion of the arm, and means movable into and out of engagement with 40 said actuating membrane whereby to control the opening of said orifice.

2. A device of the class described comprising, in combination, a collapsible chamber, an orifice chamber in communication therewith through a reed, a valve operable to close said orifice, the said valve having an arm provided with a U-shaped portion, said arm having a resilient actuating membrane thereon, and means actuated by the collapse 50 of said chamber and arranged to successively engage said membrane to cause said valve to close said orifice.

3. A device of the class described, comprising in combination, a chamber provided 55 with a movable wall, sound producing means actuated by the expulsion of air from said chamber by the movements of said wall, and means to control the operation of said sound producing means, said last named means including a pivoted spring-pressed valve movable with said wall and a resilient actuating membrane supported upon the arm of the valve, and spaced actuating means adapted 60 to engage said membrane, said membrane being interposed in the path of said actuat-

ing means whereby said membrane and said valve are rotated about the pivot therefor on the passage of said membrane past said actuating means.

4. A device of the class described, comprising in combination, a collapsible chamber, a post rigidly mounted in relation thereto, sound producing devices operable by the collapse of said chamber, a pivoted valve to control said sound producing devices, a spring for normally maintaining said valve in the open position thereof, said valve comprising a valve disc at one end thereof and a resilient actuating membrane at the other end thereof, and means on said post movable past and successively engaging said membrane to operate the valve about the pivot therefor to close said valve as said chamber collapses.

5. A device of the class described, comprising in combination, a collapsible chamber, a post rigidly mounted in relation thereto, spaced fingers mounted on said post, sound producing means operable by the collapse of said chamber, and including an orifice and a valve therefor, a normally plane resilient actuating surface mounted on and near one end of said valve, and adapted to be moved relatively to said end of said valve, a flat valve disc at the other end of said valve, a pivot for said valve intermediate of the ends thereof, and means for normally maintaining said valve in its open position, said surface adapted to be engaged consecutively by said spaced fingers as said chamber collapses for momentarily closing said valve.

6. A device of the class described, comprising in combination, a bellows, a weighted disc forming one wall thereof, and movable to collapse said bellows, sound producing means in communication with the interior of said bellows and including an orifice chamber, a spring-pressed valve pivotally mounted between the ends thereof on said orifice chamber and adapted to close said orifice, said valve being provided near one end thereof with a resilient actuating membrane movable independently of the remainder of said valve, and means movable into and out of engagement with the edge of said membrane for moving said membrane relatively to said valve to allow the passage of said means and for operating said valve through said membrane.

7. A device of the class described, comprising in combination, a bellows having a weighted disc as one wall thereof, sound producing means in communication with the interior of said bellows, said means including a chamber having an orifice therein, a pivoted valve mounted on said chamber adapted to control the opening of said orifice, and comprising a thin, flexible, resilient actuating membrane provided with a free

edge, movable independently of said valve and secured at the remaining edges thereof to one end of said valve, and a flat valve seat at the other end of said valve and stationary spaced fingers adapted to engage said membrane, the engagement of said fingers with said membrane being caused by the collapse of said bellows.

8. A device of the class described, comprising in combination, a bellows having a weighted disc as one wall thereof, a post rigidly mounted relative to said bellows, a sound producing device in communication with the interior of said bellows, means to control the sound so produced, said means including an orifice chamber and a valve for the orifice therein, said valve being pivotally mounted and provided with a resilient actuating surface, a sleeve mounted on said post and provided with an actuating finger adapted to engage said surface, said finger and said surface being relatively movable upon the collapse of said bellows.

9. A device of the class described, comprising in combination a collapsible chamber, a sound producing device in communication with the interior therewith, and including an orifice chamber and a pivotally mounted spring-held valve movable to close said orifice, the said valve having an arm provided with a membrane having one edge exposed, a post rigidly mounted relative to said chamber, a sleeve mounted on said post and provided with a finger adapted to engage said edge of the membrane, said finger and said membrane being relatively movable as said chamber collapses, and a sound producing device operable by the expansion of said chamber.

10. A device of the class described, comprising in combination, a casing having a chamber formed by a pair of heads intermediate the ends thereof, a bellows mounted on one of said heads, the sound producing devices on said head in communication with the interior of said bellows, said device including an orifice chamber and a valve to control the opening of said orifice, said valve having a resilient actuating surface, a finger movable past said surface to cause the actuation of said valve as said bellows collapses, and a sound producing device on the other of said heads in communication with said chamber.

11. A device of the class described comprising in combination, sound producing means, and means to control the sound pro-

duced, said last named means including a sound emission orifice, a movable valve member controlling emission of sound from said orifice and carrying a yieldable membrane, and means coacting with said membrane and movable against the resistance thereof to actuate said valve and control the emission of sound through said orifice.

12. A device of the class described comprising in combination, an air chamber having a fixed head and a gravity operable head movable towards and from said fixed head, a sounding reed operated by the passage of air therethrough in the movement of said latter head in one direction, a chamber receiving sound from said reed and having an emission orifice, and means to control the sound produced including a pivoted valve, and a movable valve actuating member, one of said parts carrying a yieldable membrane, and the other of said parts having spaced members successively coacting with said membrane in the movement of said movable member to intermittently actuate said valve and control the escape of sound from said emission orifice.

13. In a device of the class described, sound producing means including a reed and an air chamber having a movable wall to cause a flow of air through said reed, and means for controlling the emission of sound from said reed comprising an arm pivoted intermediate of its ends, a valve element on said arm at one side of its pivot, a yieldable member on said arm at the other side of its pivot and having a part substantially parallel with the movable chamber wall, and means coacting with said part of the yieldable member to actuate said valve arm.

14. In a device of the class described, sound producing means including a reed and an air chamber having a movable wall to cause a flow of air through said reed, and means for controlling the emission of sound from said reed comprising an arm pivoted intermediate of its ends, a valve element on said arm at one side of its pivot, a yieldable element on said arm at the other side of its pivot and having a part substantially parallel with the movable chamber wall, and spaced means carried by said movable chamber wall successively coacting with said part of the yieldable member and movable against the resistance thereof to repeatedly actuate said valve element.

In witness whereof, I affix my signature.

THEODORE HUTNIKOW.
